(57) **CLAIM**

The ornamental design for a screw-in LED bulb, as shown and described.

DESCRIPTION

FIG. 1 is a perspective view of an embodiment the screw-in LED bulb showing our new design;

FIG. 2 is a front elevation view of the screw-in LED bulb of FIG. 1;

FIG. 3 is a rear elevation view of the screw-in LED bulb of FIG. 1;

FIG. 4 is a right side elevation view of the screw-in LED bulb of FIG. 1;

FIG. 5 is a left side elevation view of the screw-in LED bulb of FIG. 1;

FIG. 6 is a top plan view of the screw-in LED bulb of FIG. 1; and,

FIG. 7 is a bottom plan view of the screw-in LED bulb of FIG. 1.
